UNITED STATES PATENT OFFICE.

RICHARD F. LOPER, OF PHILADELPHIA, PENNSYLVANIA.

MEANS FOR COVERING AND REPAIRING IRON SHIPS AND OTHER NAVIGABLE VESSELS.

Specification of Letters Patent No. 34,151, dated January 14, 1862.

To all whom it may concern:

Be it known that I, R. F. LOPER, of the city of Philadelphia, in the county of Philadelphia and State of Pennsylvania, have invented a certain new and useful Improvement in Covering and Renovating Old Iron Boats and other Vessels of Freight or Passage; and I do hereby declare the following to be a full, clear, and exact description 10 thereof, reference being had to the accompanying drawings and to the letters and marks thereon.

All vessels constructed of iron and designed to be used for conveying passengers 15 or carrying freight, either on the ocean or on rivers or lakes, propelled by steam or driven by sails may become subjects of my invention. Such vessels or boats are liable to have the iron on the outside of their hulls 20 become so thin by wear or rust as to render the vessel leaky and unsafe. Repairing such vessels by riveting metal plates over the unsound parts has been found not to answer, or to be serviceable, and it has been custom- 25 ary, previous to the use of my invention, to regard such vessels as of little or no value. When renovated under my invention such vessels are stronger and of greater practical value than a new vessel of wood or of iron. 30 By the drawings forming part of this specification my invention is shown applied to an old iron vessel, Figure 1 thereof being a view by transverse vertical section between midship and stern-post, and Fig. 2 a view 35 by longitudinal vertical section of the keel, keelson, stem-post and stern post.

In each of these figures where like parts are shown like marks and letters are used to indicate the parts. 40 In carrying out my invention I take from the water and place in suitable condition to be operated upon, the boat or vessel, the iron on the outside of the hull of which has become so thin by wear or rust that the vessel 45 may leak or be unsafe, and with wooden timber form a keel (a), stem-post (b), and stern-post (c), to fit the iron keel (d), stern-post (e) and stern-post (f). A rabbet should be cut in the wooden keel for the garboard 50 streak and in the stem-post and stern-post for the wood ends. Holes should be cut in

the old iron hull (g) to receive the fastenings of the outside plank (h). Put on the planking for the bends and then the garboard streak (i), and plank up the sides in 55 the usual manner, or plank in any other way the shipbuilder may think proper. The plank may be secured to the iron hull by means of screw-bolts (j), or in any other suitable manner. I prefer fastening by 60 screw-bolts in the following manner: Cut a hole in the iron hull in every part where you wish to fasten the planking, fit the plank to the bottom or sides of the vessel, then go on the inside and placing the auger in the hole 65 through the iron hull bore through the wooden plank, ream out the hole in the outside plank to a proper size to receive the wooden plug (k) which covers the head of the bolt (l) that fastens the plank to the 70 iron hull. This being done, and the bolt being a good fit, put a nut (m) on the end of the bolt inside of the vessel and screw the plank firm against the iron hull; then put in the plug on the outside planking in the 75 same manner as plugs are put in the deck of the vessel.

I recommend that the bolts and plugs should be dipped in thick white lead or paint before they are put in the planking or 80 driven in the vessel; this will prevent the bolt rusting and leaking.

I had on hand two iron steamers and a barge that became unsafe, owing to wear and rust. I have had them planked as 85 described in this specification and I would rather have them when finished in this way than a new iron boat or a new wooden boat of the same size.

What I claim as my invention and desire 90 to secure by Letters Patent is—

The planking of old iron boats or second-hand vessels as set forth, whereby a safe and good vessel or boat can be made out of any iron vessel or boat after the iron has become 95 thin by wear or rust as described.

This specification signed this 1st day of March 1861.

R. F. LOPER.
